UNITED STATES PATENT OFFICE.

MARTIN F. MORAN, OF NEKOMA, KANSAS.

INKWELL.

Application filed February 24, 1925. Serial No. 11,251.

To all whom it may concern:

Be it known that I, MARTIN F. MORAN, a citizen of the United States, residing at Nekoma, in the county of Rush and State 5 of Kansas, have invented new and useful Improvements in Inkwells, of which the following is a specification.

This invention relates to ink wells and has for one of its objects the provision 10 of an article of the class described which is simple in construction, being devoid of moving parts, leak-proof and readily cleaned.

A further object of the invention is to 15 provide automatic means associated with the funnel of the ink well for accelerating the drainage, back into the reservoir thereof, of any ink that may be splashed upon the wall of said funnel.

20 A still further object of the invention is the construction of an improved joint between the cover and body of the ink well which will ordinarily be leak-proof, the interlocking elements of said joint being positioned remote from the zone of possible 25 leakage so that they will not become inseparable due to the drying of ink in the interstices therebetween.

Other objects of the invention will appear 30 as the description develops.

In the drawing:

Figure 1 is a perspective view of my improved ink well showing the cover and body portion separated.

35 Figure 2 is a vertical section taken on a diametrical plane.

Figure 3 is a cross section taken along the line 3—3 of Figure 2.

40 Figure 4 is a diagram illustrating the effect of the converging ridges within the funnel upon a drop of ink through surface tension.

Figure 5 is a cross section showing a modified form of the invention.

45 Figure 6 is a cross section through another modification.

Figure 7 is a section taken along the line 7—7 of Figure 6.

50 Referring now in detail to the several figures, the numeral 1 represents the body, and 2 the cover of the ink well. The body 1 is imperforate at the bottom. The cover 2 is formed with a re-entrant funnel 10 terminating below the liquid level within the reservoir 3 of the ink well when the latter is filled with ink. In Figure 2,

which shows the cover and body in assembled position, it will be observed that a reservoir is formed between said parts which is designed to be filled with ink to about 60 the level indicated, leaving an annular air space between the funnel and the inner side walls of the cover. The joint between the cover and body of the ink well is arranged in the zone of this air space and 65 consists of a flat annular shoulder 4 formed within the cover which contacts with the flat terminal edge 5 of the body. Said shoulder and edge are each provided with an annular packing seat preferably of semi-circular cross section, which seats match 70 when the cover and body are secured together and form an annular channel in which is clamped a rubber or other compressible gasket 6, preferably of circular cross section. Below the gasket 6 the top and body are formed with telescoping cylindrical sides 7 and 8 which preferably make a close fit with one another, said telescoping sides terminating in threaded portions 9 and 10, 75 respectively, by means of which the cover and body may be screwed together, compressing the gasket 6 and making a leak-proof joint. On account of the elongated nature 80 of the telescoping sides of the cover and body the threaded portions of these parts are remote from the gasket 6 so that should a leak occur through any defect in the gasket or from any other cause the slight amount 85 of ink oozing through said gasket will not reach the threads so that the latter will remain clean and will not become inseparably stuck together due to the drying of ink in the interstices between them.

90 The funnel 10 is preferably formed with 95 downwardly converging ridges or grooves 11 extending at least as far as the normal level of ink within the mouth of the funnel. These ridges or grooves perform an important function. Surplus ink is frequently 100 shaken from the pen-point into the funnel and lodges upon the walls thereof. In ordinary constructions this surplus ink rests where it lodges until it evaporates, leaving 105 a sedimentary deposit. In the present construction a drop of ink so shaken upon the wall of the funnel lodges between two ridges, contacting with the sides thereof, and, by reason of the converging nature of the ridges, being subject to a greater surface tension at its lower side than at its upper side, is caused to be rapidly drawn down 110

the wall of the funnel into the body of ink in the mouth of said funnel with a considerably greater acceleration than could be effected by gravity alone. In this manner 5 the ink is returned to the reservoir before it evaporates, thus avoiding loss of ink and also avoiding sedimentary deposits upon the wall of the funnel. A pivotally mounted gravity operated valve 12 controls the 10 mouth of the funnel, said valve being maintained normally closed by means of the weight 13 at the end of the stem and opened by pressure of the pen. It is to be understood that the integrity of the invention is 15 not disturbed by the omission of said valve.

One of the practical drawbacks to the cheap construction of a two-part glass ink well is the difficulty of molding the threads so that they will perfectly match. The modified 20 form of my invention illustrated in Figure 5 embodies a construction which avoids the interengagement of glass threads and thereby avoids this difficulty. In this form of the invention I have provided a glass 25 body 12 having a smooth exterior lateral surface over which the top portion 13 telescopes, the body projecting a slight distance below the top portion when the latter rests upon the gasket 16.

30 The top portion 13 is threaded at its lower end, and a cap 14 of hard rubber or other suitable material is provided which screws upon the threaded end of the top portion and forces the body inwardly against the gasket 16, compressing the latter into a fluid-tight 35 condition. The top portion may be of any suitable material, including glass, for there is no practical impediment to having a molded glass thread mesh with a thread in 40 hard rubber. When it is desired to take this ink well apart for cleansing, the rubber cap 14 is removed and a rod of any suitable nature thrust into the opening 17 at the mouth of the reservoir. The ink well is 45 then inverted and the outer end of the rod tapped against a firm surface. This dislodges the body from any adhesion which may exist in the joint between it and the top portion permitting the two parts readily to 50 separate.

In Figure 6 is shown still another form of the invention in which the top portion 18 and body 19 are preferably made of glass with a gasket 20 interposed in the joint between said parts, one only of said parts, that is to say the body, being threaded as shown at 21. The top portion is provided with an annular shoulder 22 extending thereabout adjacent the threaded end of the bottom, and a threaded ring-nut 23 arranged to engage the body of the ink well and having an overhanging shoulder 24 engageable with the annular shoulder 22 for drawing the parts

of the ink well together. Separation of this ink well is effected by removing the ring-nut. It is to be understood that the same inventive principle pervades all of the illustrated forms of my invention and that they distinguish from one another merely in the details of the construction by which the invention is carried out. It is also to be understood that the several forms of ink well illustrated and described in the present application are merely exemplary of many other equivalent constructions to which the inventive principle may be applicable.

While I have illustrated and described what I consider to be practical, and perhaps, preferred embodiments of my invention, yet it is to be understood that departure from the details of the construction as shown and described may be made within the scope of my invention unless specifically excluded by the limitations expressly set forth in the claims.

Having described my invention what I claim as new and desire to secure by Letters Patent, is:—

1. An ink well comprising a cover formed with a re-entrant funnel and with an internal annular shoulder, a body telescoping within said cover and having an annular terminal edge co-acting with said shoulder, a cap engaging said body and screwed upon the lower end of said cover, and a gasket fitted between said shoulder and edge and compressed when said cover and body are screwed together.

2. An ink well comprising a cover formed with a re-entrant funnel and with an internal annular shoulder, a body having a smooth exterior surface telescoping within said cover and having an annular terminal edge co-acting with said shoulder, said body projecting slightly below said cover, a gasket fitted between said shoulder and edge, and a cap engaging the projecting end of said body and screwed upon the lower end of said cover for compressing said gasket when said cover and body are screwed together.

3. An ink well comprising a cover formed with a re-entrant funnel and with an internal annular shoulder, a body having an imperforate bottom, telescoping within said cover and having an annular terminal edge co-acting with said shoulder, said body projecting slightly below said cover, a gasket fitted between said shoulder and edge, and a cap engaging the projecting end of said body and screwed upon the lower end of said cover for compressing said gasket when said cover and body are screwed together.

In testimony whereof I have hereunto set my hand.

MARTIN F. MORAN.
